UNITED STATES PATENT OFFICE.

CLAUDE B. DAVIS, OF RICHMOND, VIRGINIA, ASSIGNOR OF ONE-HALF TO MARION ALLEN AND ONE-FOURTH TO WILLIE THOMAS BRAGG, BOTH OF RICHMOND, VIRGINIA.

TOLL-COLLECTING MECHANISM.

1,350,958.

Specification of Letters Patent. Patented Aug. 24, 1920.

Application filed November 23, 1918. Serial No. 263,864.

To all whom it may concern:

Be it known that I, CLAUDE B. DAVIS, a citizen of the United States, residing at Richmond, in the county of Henrico, State of Virginia, have invented certain new and useful Improvements in Toll-Collecting Mechanisms; and I do hereby declare the following to be a full, clear, and exact description of the invention, such as will enable others skilled in the art to which it appertains to make and use the same.

This invention relates to toll collecting mechanisms and particularly to mechanisms for collecting entrance fees to places of entertainment such as moving picture theaters.

Ordinarily a ticket seller is employed and a ticket collector, involving the payment of two salaries in addition to the expense of the tickets and furthermore, excepting by counting the remaining tickets from a previously known supply, there is no way of keeping an accurate account of the number of admissions paid for and upon which the present tax is based.

It is the object of the present invention to provide a pay as you enter arrangement in which each person may have admittance only after having paid his entrance fee, subsequent manipulation of the apparatus serving to release a turn-stile, dump the fee and register its payment.

In the drawings:

Figure 1 is a horizontal sectional view through the lobby wall, the cashier's booth and the turn-stile of an arrangement embodying the present invention.

Fig. 2 is a section on line 2—2 of Fig. 1, the turn-stile and some other details being in elevation.

Fig. 3 is a perspective view showing the interior of the cashier's booth, the counter being in section.

Fig. 4 is a vertical section through the turn-stile latch.

Fig. 5 is a detail transverse section through the central spindle and one of the wing sections of the turnstile, the retaining bolt being shown in plan view.

Referring now to the drawings there is shown at 10 the rear wall of the lobby of a theater or other place of entertainment for entrance to which a fee is charged, the entrance doorway being indicated at 11 and

the exit doorway at 12. Beyond the partition 10 and to the right of the entrance doorway in the plan illustrated, is the partition wall 13 of the cashier's booth and spaced from this partition wall and at the opposite side of the entrance doorway is mounted the vertical spindle 14 of a turnstile.

The upper end of the spindle 14 has a trunnion 15 journaled in a bracket 16 upon the top of the turnstile housing 17 through which the upper rounded end of the spindle projects while the lower trunnion 18 of the spindle is journaled in a floor plate 19. The spindle 14 is illustrated as rectangular in cross section and it is provided with a longitudinal groove 20 in each of its faces, that receives the corresponding edge of a wing 21 of the turnstile. It will be noted that the wings project oppositely from the spindle in pairs and through the wings of each pair and the spindle there are engaged removable tie bolts 22. The wings 21 are illustrated as solid doors for winter use and this removable arrangement permits of the substitution of frames with screen coverings for summer use.

Upon the upper face of the floor plate 19 is formed an annular ratchet 23, concentric with the trunnion 18, over which drags a pawl 24 carried by one of the turnstile wings 21 this arrangement permitting the turnstile to rotate in a direction to permit of entrance and prevent exit.

The turnstile is held normally against rotation to permit of entrance, through the medium of a sliding detent 25 mounted in a U-shaped frame 26 within the cashier's booth and having the free ends of its sides turned laterally and bolted against the inner face of the booth partition 13, through which one end of the detent normally projects. This projecting end of the detent is provided with a notch 27 and resultant fingers 28 and 29, the notch being of a width and depth sufficient to receive and hold, interchangeably, the free longitudinal edge portions of the turnstile wings 21. These free longitudinal edges are provided with wear shoes 30, the forward faces of which are beveled where they successively engage the correspondingly beveled outer face of the detent finger 29 to slide the detent rear-

wardly and permit of movement of the wings into position for engagement in the notch 27.

The detent 25 is held normally projected 5 into position to engage a turnstile wing, through the medium of a helical spring 32 disposed between the inner end of the detent and the bight of the U-shaped frame 26 and through which helical spring there extends 10 the bolt 34 carried by the detent 25 and which extends through and beyond the bight 33 where it is provided with a pair of nuts 35 which when locked one against the other, limit the extent of projection of the detent 15 through the partition 13 and serve to properly position the beveled face of the finger 29 so that it will be properly engaged by the wear shoes 30 to effect retrograde movement of the detent.

20 In order to manually retract the detent when an entrance fee has been paid, the detent is provided with a depending ear 36 behind which is engaged the crank 37 of a shaft 38 mounted in bearings 39 and 40 that 25 depend from the counter 41 that projects into the cashier's booth from the sill of the window opening 42 in the booth partition 13. The shaft 38 is provided with an operating handle 43 that extends above and to one side 30 of the counter 41 and it will be understood that when this handle is drawn rearwardly, the shaft 38 is rocked and the detent retracted against the action of the spring 32.

The detent mechanism is operated to release the turnstile only after payment of 35 the entrance fee, which is deposited upon a tray 44 fixed to the shaft 38 and normally closing an opening 45 in the counter 41. The opening 45 leads to a coin receptacle 46 mounted upon a foot 47 that depends from the counter supporting bracket 48 and is provided with a door having an ordinary form of lock. When the shaft 38 is moved an angular distance to retract the detent 40 and release the turnstile, the tray is tilted so that the coin or coins of admission placed upon it, slide from it to the coin receptacle below.

45 The shaft 38 is continued beyond its crank 37 where there is fixed to it a supplemental crank arm 49 between the terminal ears 50 of which is disposed the lower end of the pull rod 51 of a registering mechanism 52 the operating lever 53 of which is received between the ears 54 at the corresponding end of the rod 51. The rod 51 is connected with the levers 49 and 53 through the medium of pivot pins 55 and 56 respectively which are headed at one end 55 and are each provided at its other end with a pair of perforations to receive a cotter pin 57 and a seal wire 58, respectively.

In use, a person presents himself at the cashier's window 42 and deposits the entrance fee on the tray 44, whether or not

change has been made for him on the counter 41. The cashier then operates the handle 43 to retract the detent, tilt the tray 44 to discharge the coin and operate the registering mechanism to register the receipt of a stipulated fee. When the person has passed into the turnstile and has given initial movement to it, the lever 43 is released and the detent returns to position to again engage and hold the turnstile.

To hold the turnstile closed when desired, a locking pin 59 is engaged through perforations 60 and 61 that are formed respectively in the frame 26 and detent 25 and which register when the detent is projected.

By reason of the fact that the ear 36 is in the form of a hook behind which the crank 37 lies, the detent 25 when forced rearwardly as the turnstile engages it, will not rock the shaft 38 and operate the registering mechanism.

What is claimed is:—

1. The combination with a turnstile of a detent for the turnstile, a dumpable coin tray and a single means for retracting the 90 detent and simultaneously dumping the coin tray.

2. The combination with a turnstile of a retractile detent for holding the turnstile at times against operation, a dumpable 95 tray to receive a fee, a single means for simultaneously retracting the detent and dumping the tray and a single means connected with both the tray and the detent for registering said simultaneous operations. 100

3. The combination with an entrance way, of means for closing the entrance way at times, means for holding the closure at times in operative position, a receiver for coins and a single means having connections for retracting the closure holding means and for shifting of the coins from the receiver. 105

4. The combination with an entrance way, of a closure movable into and out of operative relation to the entrance way, a detent for holding the closure at times operative, a rock shaft, connections between the rock shaft and detent for retracting it, a coin tray carried by the shaft and movable therewith into position when the detent is retracted to dump therefrom coins placed thereon and means for oscillating the rock shaft. 115

5. The combination with an entrance way, 120 of a closure movable into and out of operative relation to the entrance way, a detent for holding the closure at times operative, a rock shaft, connections between the rock shaft and detent for retracting the latter, 125 a coin tray carried by the shaft and movable therewith into position when the detent is retracted to dump therefrom coins placed thereon, a registering mechanism connected with the shaft for registering each oscillation. 130

tion of the latter and means for oscillating the rock shaft.

6. The combination with a turnstile of a detent for the turnstile, mechanism for retracting the detent at times, a dumpable coin tray and means including an element of the detent retracting mechanism, for dumping the tray simultaneously with the retraction of the detent.
- 10 7. The combination with a turnstile, of a detent for the turnstile, mechanism for retracting the detent at times, a dumpable coin tray and means including an element of

the detent retracting mechanism, for dumping the tray simultaneously with the retraction of the detent, and means also operably connected with said detent retracting mechanism, for registering the successive simultaneous operations of the detent and coin tray.

In testimony whereof I affix my signature in the presence of two witnesses.

CLAUDE B. DAVIS.
